UNITED STATES PATENT OFFICE.

LASZLO PONGRACZ, OF NEW YORK, N. Y.

LOCK.

Application filed November 3, 1922. Serial No. 598,710.

To all whom it may concern:

Be it known that I, LASZLO PONGRACZ, a citizen of Hungary, and residing at 187 East 3rd Street, New York, N. Y., have invented

5 a new and useful Improvement in Locks, of which the following is a specification.

This invention relates to locks for doors of houses, stores and similar places where strong and safe locking means are desired, 10 but may be used for almost any purpose for which locks are employed at present. The main object of this invention is to provide a device of this character which will have exceptionally strong locking means, a long 15 travel for its bolt, and which, at the same time, may be opened or closed with very little exertion of force, by a comparatively simple key, and with an easy and light turning motion of the same.

20 Another object of my lock is to provide a plurality of safety devices, using very simple and inexpensive means for the same which, nevertheless, will give perfect security against an unauthorized opening of the 25 lock.

Still a further object of my device is to provide a lock which is substantial in construction and has such locking means as best adapted to resist the strongest burglarizing efforts.

30 Still another object of my invention is to provide a lock of the above mentioned character which is simple in construction, has comparatively few parts, is easy to manufacture and to assemble and is adapted to be used with almost any kind of doors, like left handed, right handed or double doors.

For a full description of the invention and the merits thereof and also to acquire a 40 knowledge of the details of construction of the same for effecting the various results mentioned hereinbefore, reference is to be had to the following description and accompanying drawings.

45 While the essential and characteristic features of the invention are susceptible of modification, still the preferred embodiment of the invention is illustrated in the accompanying drawings, in which:—

50 Fig. 1 is a plan view of my lock seen from the outside of the door; the covering plate of the same, and certain other parts having been removed, and portions of it being broken away so as to permit the use 55 of a larger scale for the drawing;

Fig. 2 is a plan view of my assembled de-

vice seen from the outside of the door to which it is applied, portions of the same having been removed;

Fig. 3 is a similar view of the same from 60 the inside of the door;

Figs. 4, 5, 6, 7 and 16 are detail views of parts of my inside locking mechanism;

Figs. 8 and 9 are elevational and bottom views, respectively, of my key, while 65

Figs. 10, 11 and 12 are views of my improved key hole, and the safety devices employed therein;

Fig. 13 is a diagrammatic plan view of my 70 assembled lock seen from the outside of the door and showing its bolt in a locking position;

Fig. 14 is a cross sectional view of a portion of my device, the section being taken on the lines 14—14 of Figs. 2 and 3, portions 75 of the lock having been removed;

Fig. 15 is a plan view of the excenter used in closing and opening my lock;

Figs. 17 and 18 are detail views of the element in my lock used to close or open the 80 same from the inside.

Referring more in detail to the drawings, the operating mechanism of my lock is housed in a preferably rectangular casing 19 having a bottom 20 arranged towards the 85

inside of the door. A base plate 21 is secured to the bottom of the casing and used to arrange portions of the operating mechanisms thereon and to give the moving elements a secure and smooth guiding surface. 90

The main locking element is a heavy bolt 22, guided by a channel 23 secured to the door towards the inside of the same and also by a heavy cover plate 24, preferably passing over the whole width of the door, strongly 95

secured to the same and covering the center portion of my lock from the outside (Fig. 2). The closing and opening mechanism of my device mainly consists of a system of hinged links 25, operated by an excenter de-

vice 26, which in turn is controlled by the key 27 (Figs. 8 and 9), fitting into the opening 28 in excenter device 26. Fig. 1 shows the bolt and the operating devices in 100

open position. By turning the excenter 26 in the direction of the arrow 29, its outwardly extending pin 30 will engage the hole 32 in a semi-circular arm 31 and move the same in the general direction of arrow 29, as will be more fully explained herein- 105

after. This movement will exert a pressure 110 on the link member 33 hingedly connected at

the one end of the same to the extension 34 on semi-circular link 31, and at the other end to the inside termination 35 of the bolt 22, and thereby cause said link, as well as 5 the bolt 22, to move in a generally right handed direction (Fig. 1). This will cause the bolt 22 to move into a locking position. In the portion of link 33 adjacent to the bolt 22, a further link 36 is connected to the 10 same and operates a final link 37, hingedly connected to the lower end of link 36. When locking the door, the key, and with it the excenter 26, will execute about one half of a revolution and the link elements mentioned hereinbefore will take up the position shown in Fig. 13, bolt 22 having made a comparatively long travel, assuring a firm locking grip of the same.

A sheet metal locking element 38 is pivotally secured, as at 39, to the bottom 20 of the casing in its lower portion and carries two upstanding posts 40 and 41 at its ends. A further locking element is secured in the form of a small metallic plate 42 to the 25 outside end of the final link 37, carrying a similar, but comparatively heavier and stronger, upstanding post 43 at its lower end adjacent to the vertical outside surface of the locking link 37. A spiral spring 44 connects the posts 41 and 43 passing around the post 40. When the lock is set into a closed position as shown in Fig. 13, the locking plate 38 will be moved upwardly under the pressure of the spring 44 and will 30 engage the locking post 43, thereby terminating the forward motion of bolt 22. A second spring 45 is also secured to post 43 and connects the same with a post 46 in the upper left hand portion of my device and 35 serves to steady and equalize the movements of terminating link 37 and locking plate 38. Similarly, a spiral spring 47 engages an extension 48 on the further end of circular starting link 31 and connects the same to the 40 post 46, thereby steadyng its motion.

As will be seen by inspecting the drawings, the link mechanism employed in my lock will insure a steady and quick opening or closing of the same and a long travel for its 45 bolt 22 with a comparatively short semi-circular movement of the excenter 26 and of the key employed in the same. At the same time the link movement will insure that a small force exerted on the key will 50 be able to move a comparatively heavy bolt 22. Said link movement and excenter will, further on, provide a comparatively strong resistance against the forcible backward movement of the bolt 22, or the forcible 55 opening of the same from its locking end 49.

A heavy strong plate 24 is used to cover my lock towards the outside of the door (Fig. 2). The same is sunk into the material of the door, crossing its entire width, and 60 hidden from the outside by some appropri-

ate covering. At the one end of the same, I may employ a hinge device 50 securing it to the stationary elements of the building or the other object to be locked and giving additional strength and safety to my locking means for said door. 70

Towards the inside of the door, I employ the channel 23, mentioned hereinbefore, with its open side turned to the plate 24 and forming a guide for the bolt 22. The surface of the bottom 20 of my case, turned to the inside of the door, carries certain inside opening and locking elements 51 which co-operate with the safety devices employed in the keyhole 52, secured to the heavy plate 24, on the outside of the door (Fig. 2). The elements and constructions of this keyhole and inside safety and opening or locking devices and their cooperation will now be more fully described. 75

The keyhole is a hollow casting, (Figs. 10, 11 and 12), secured to the plate 24 by its flange 53. Its wall 54 is recessed for a portion of the same adjacent to the plate 24, as at 55, and has a slot 56 cut therein. A sheet metal case 57 of box like structure is applied over said slot and secured to the flange 53 by screws 58 or by any other suitable means. Two bearings 59 are arranged on the inside 80 of the vertical walls of said sheet metal box and a small shaft 60 is rotatably arranged therein, carrying a double lever 61. Said lever has at the end of its forward branch a downwardly extending nose 62 which in its 85 normal position is pressed into the recess 55 of the keyhole by spiral spring 63, resting against the top wall of the box 57; while the opposite branch 64 of the double lever extends into the slot 56 in the flange 53 of the keyhole and contacts with the outside 90 surface of the plate 24, thereby preventing the forward end 61 from entirely dropping into the recess 55. The plate 24 has a hole 66 at this point corresponding to the keyhole and adapted to receive an upper extension of the excenter which carries further 95 operating and safety devices to cooperate with the key. 100

The construction of said devices in the excenter and their connection with the keyhole devices is shown in a larger scale on Fig. 14. The excenter 29 has two cylindrical extensions 67 and 68 in an upward and downward direction, respectively. A bore 69 passes through the center of the excenter and its two extensions and said two extensions also have transversal slots 70 and 71 cut at their ends coincident with the bore 69 (Fig. 15) 105 passing across their entire widths and to a certain depth in them. A small pin 72 is placed in the lower portion of said bore 69 having certain inside locking and securing elements arranged on its inside (lower) end—to be more fully described herein-after—and being steadily pressed in an up- 110

ward direction by spiral spring 73 arranged in the bore 69 around the pin 72 and leaning against the head 74 of said pin. Said head is of a somewhat larger diameter than the rest of the pin and slidably fits into the bore 69. Underneath the excenter 29 is mounted the circular starting link 31 connecting with the further link 33, said links having downwardly extending bosses 75 at certain places which serve as guiding surfaces on the plate 21. Similar bosses 76 are employed on the upper surfaces of said links at certain points of the same serving to guide them on the upper plate 24 in their sliding movements.

The key adapted to pass the obstacles placed in the keyhole and in the bore 69 of the excenter and adapted to catch said excenter and to turn the same therewith is illustrated in Figs. 8 and 9. Its stem is preferably cylindrical and has a small cylindrical pin 77 at its lowermost extremity which is continued in a portion where the two sides of the cylinder have been removed, leaving a small wall 78 running diametrically across the bottom of the key. The key is then continued in the full circular lower portion 79 of the stem, said lower circular portion being divided from the upper circular stem 80 by a semi-circular groove 81. The key cannot pass through the keyhole in a position where the wall 78 would present its circular smaller outside end to the nose 62 in the keyhole, since it would hit the same and would be prevented from further penetration. The key must be turned in such a position that the wall 78 will pass with its broader surface (nearer the center of the stem of the key) underneath the excenter 62 and will hit the same with the lower edge 82 of the cylindrical portion. Thereupon the key is turned and the wall 78 will gradually press the excenter 62 out of the recess 55, against the force of the spring 63, and the full cylindrical portion can pass underneath said excenter 62. The key now must be turned until the wall 78 will be in alignment with the slot 70 across the upper cylindrical extension 67 of the excenter 29 and can engage the same. Thereupon an inward pressure must be given to the key for two reasons: first, to move the pin 72 inwardly and permit the wall 78 to fully engage the slot 70 and secondly because certain locking elements (to be described presently) will still prevent the turning of the excenter until they are put out of engagement by the inward movement of the pin 72. The axial end pin 77 of the key serves to move said pin 72 inwardly, upon coming in contact with its head 74. When the inward movement of the key is terminated, the lower edge 82 of the cylindrical portion of the stem being pressed in close contact with the upper surface 83 of

the excenter extension 67, the key can be turned around and will rotate the excenter which in its turn will move the starting circular link 31 by making use of the pin 30, as described hereinbefore. The extension 62 on the double lever in the keyhole wall will snap into the circular groove 81 in the key and keep said key in its position, at the same time permitting a free rotation.

My lock can be opened from the inside without any key and independently of the mechanisms arranged in the keyhole. It also has such elements connected with its inside opening devices that will prevent the opening of the same from the outside before they are put out of engagement. For this purpose the pin 72 is extended inwardly to the inside of the door and provided with screw threads adjacent to its inside termination 84. An inside lifting device 85 is threaded on said pin, made of sheet metal and having the design shown in Fig. 14 and more in detail in Figs. 6 and 7, and is held down by a spring 86 which is in secure threaded engagement with the end 84 of the pin 72 and made fast in its position by a nut 87. The detailed design of said spring is shown in Fig. 16. The downwardly bent extension 88 of the same will be secured to the bottom 20 of the casing of my lock (Fig. 3) while the upper branch 86 will be provided with a threaded hole 89 to engage the lower end 84 of pin 72. Underneath said spring 86 and lifting device 85, I employ a bent guiding and locking plate 90, secured to the bottom plate 20, as at 91, and showing the detail construction illustrated in Figs. 4 and 5. The lifting device 85 and bent guide plate 90 are normally in the same direction, one above the other, and the extension 92 at the end of lifting device 85 reaches inwardly in front of the end 93 of the bent guide plate 90. The spring 86 is arranged in a substantially perpendicular direction to that of the lifting device and bent guide plate (Fig. 3). Extending in a generally opposite direction to that of the spring is placed the innermost of the elements of the inside devices of my lock which is the opening lever 94 (Figs. 3, 15, 17 and 18). Said opening lever is preferably made of sheet metal and has an extended head 95 with two suitably cut stops 96 and 97 and two upstanding teeth 98, adapted to engage the cross slot 71 in the lower extension 68 of the excenter 29. In the closed position of my lock, spring 86 will exert a pressure on the lifting device 85 and place its tooth 92 in engagement with the shoulder 96 of the opening lever 94, thereby preventing the rotation of said lever and the opening of the lock from the inside. When it is desired to open the lock, the lifting device 85 is pulled outwardly by handle 99, against the force of the spring 130

86, the tooth 92 lifted out of engagement and the lever 94 turned by the handle 100, rotating the excenter 26 and opening the lock. After this, the catch 99 is released 5 and the tooth 92 will snap back into engagement with the opposite shoulder 97, securing the lock in an open position. It is obvious that when it is desired to open or close the lock from the outside of the door, 10 by using the key, the tooth 92 must first be removed from engagement with the shoulders 96 and 97, respectively, and this is effected by the terminal central pin 77 of my key, when the pin 72 within the excenter is pushed inwardly thereby.

15 What I claim as my invention is:—

1. In a lock of the class described, a casing, a bolt within said casing, an excenter in said casing connected to said bolt by a link 20 mechanism; a key adapted to turn said excenter and set said link mechanism and said bolt into motion in an inward or outward direction; a pivotally mounted plate within said casing connected with said link mechanism and adapted to terminate its motion, 25 and springs within said casing secured to said link mechanism, said excenter and said plate and adapted to steady and regulate their movements.

2. In a lock of the class described, a casing, a bolt within said casing, a guide for said bolt, an excenter in said casing connected to said bolt by a link mechanism; a key adapted to turn said excenter and set 30 said link mechanism and said bolt into motion in an inward or outward direction within said casing and said guide; a pivotally mounted plate within said casing connected with said link mechanism and adapted to terminate its motion; axial extensions on said excenter extending in both directions perpendicularly to said casing within the inside and outside of the door, respectively, to which said lock is applied, an axial 35 hole through the center of said excenter and its extensions, diametrical slots at the two ends of said extensions; a key adapted to engage the outside one of said slots and turn the excenter thereby; means to engage the 40 inside one of said slots and rotate said ex-

center therewith, and a locking pin and spiral spring arranged within said axial hole adapted to control said means.

3. In a lock of the class described, a casing, a bolt within said casing, a guide for said bolt, an excenter in said casing connected to said bolt by a link mechanism; a key adapted to turn said excenter and set said link mechanism and said bolt into motion in an inward or outward direction within said casing and 55 said guide; a pivotally mounted plate within said casing connected with said link mechanism and adapted to terminate its motion; springs within said casing secured to said link mechanism, said excenter and said plate 60 and adapted to steady and regulate their movements; axial extensions on said excenter extending in both directions perpendicularly to said casing within the inside and outside of the door, respectively, to which 65 said lock is applied, an axial hole through the center of said excenter and its extensions, diametrical slots on the ends of said extensions; a spring pressed locking pin within said hole having means to normally prevent 70 the rotation of said excenter; a hollow cylindrical key guide mounted on the outside of said door co-axially with said locking pin; a lever rotatably mounted within the 75 wall of said hollow cylinder, a spring engaging said lever and normally projecting its head within the keyhole; a cylindrical key having means thereon to push said lever head out of said keyhole, to engage the slot on said outside excenter extension and to 80 press said locking pin in an inward direction releasing the inside locking means and means on the inside of said lock adapted to 85 release said locking means and to rotate said excenter from the inside of the door, 90 independently of said key.

In testimony whereof, I have signed my name to this specification in the presence of two subscribing witnesses, this 1st day of November, 1922.
